UNITED STATES PATENT OFFICE.

TOMAS FRANKLIN GERKEN, OF MIRANDA, SOUTH DAKOTA.

AIR CLEANER FOR MOTOR VEHICLES.

Application filed October 23, 1926. Serial No. 143,754.

This invention relates to means for cleaning the air forming part of the fuel charge of an automobile and the general object of the invention is to provide a device of this character which is relatively simple and compact, which may be readily mounted upon all standard makes of automobiles, which will considerably reduce the amount of fuel used, which will prevent the inlet of dust, carbon, and other foreign matters into the carburetor and so into the cylinders of the engine, and which will act to moisten the air passing to the carburetor.

A further object is to provide a device of this character which includes a washing tank containing liquid with a plurality of tubes running downward into the liquid through which the air to be cleaned is drawn, these tubes discharging below the level of the liquid and there being a clean air outlet receiving cleaned air as it passes up through the liquid and carrying this cleaned air out to the carburetor.

A further object is to provide improved means whereby water within the air cleaning tank may be kept to a uniform level and another object is to provide means whereby the cleaned air may be heated or warmed prior to its introduction into the carburetor of the engine.

Other objects have to do with the details of construction and arrangement of parts to appear more fully hereinafter.

My invention is illustrated in the accompanying drawings wherein;

Figure 1 is an elevation of an air cleaner constructed in accordance with my invention;

Fig. 2 is a vertical sectional view through the air cleaner;

Fig. 3 is a transverse sectional view on the line 3—3 of Figure 1, showing the water inlet valve and its controlling means;

Fig. 4 is a side elevation of the elbow 37.

Referring to these drawings 10 designates a glass jar or tank which in actual practice will be about 5½" high and 4½" in diameter. Extending across the top of this jar is a tube sheet 11 which at its margin rests upon a rubber packing ring 12 disposed within a seat 13 formed in the wall of the jar. Soldered to this tube sheet 11 is a dome 14. The central portion of the tube sheet 11 is formed with a relatively large opening 15 from which extends, upward through the dome, the clean air outlet pipe 16. The tube sheet carries a plurality of downwardly directed copper

tubes or flues 17 which are attached at their upper ends to the flue sheet and open through the same. These flues extend nearly to the bottom of the jar 10. The flues pass through a perforated bubble sheet 18, which is preferably made of copper and fits loosely within the glass jar, the greater portion of this bubble sheet being perforated as at 19. Thus all the air which passes downward through the tubes 17, passes upward through the water which fills the bottom of the tank below the lower ends of the tubes 17 and must pass upward through these perforations 19 into the space above the bubble sheet and from thence out through the clean air pipe 16.

Entering the dome 14 is an air inlet pipe 20 which may be made of copper or other suitable material and is attached to the dome in any suitable manner. For the purpose of keeping the water in the lower portion of the tank at a predetermined level I provide a water inlet pipe 21 which extends upward through the dome from the bubble sheet 18 adjacent one margin of the bubble sheet and extends upward over the dome to a point near the center thereof, to a casing 21^a.

Connected to the casing 21^a is a flexible tube 22 which extends to the tank 23 mounted upon the automobile at any suitable point. The casing has a sediment trap 21^b. The passage of water from pipe 22 to pipe 21 is controlled by a valve 24 carried by rocker 25 pivoted at 26, and carrying a weight 27 at one end, this weight acting to close the valve, while the other end carries an adjusting screw 28. This adjusting screw acts to limit a vertically extending float rod 29 which extends downward through a tube 30. This tube 30 extends centrally through the clean air outlet pipe 16 and opens at the upper end of this pipe and at its lower end passes through the screen 19 and constitutes a guide for the float rod 29. This rod at its lower end is connected to a float 31. In the operation of this part of the mechanism, when the float falls by reason of the decrease of water in the tank or jar, valve 24 will open communication between pipe 22 and pipe 21 and the suction of the engine will cause water to be drawn from the tube 22 and from the tank 23 into tank 10.

The air inlet pipe 20 may extend in any desired direction but preferably extends downward approximately parallel to the axis of the jar, as illustrated. The clean air outlet pipe 16 extends upward through the dome

and then at right angles, as at 32, and then extends downward, as at 33, and is connected to the carbureter in any suitable manner.

Disposed within the clean air outlet pipe 16 and preferably in the horizontal portion 32 thereof, is a check valve 34 which is hinged so as to open upon each suction stroke of the engine to permit the passage of air but which will close in case of backfiring. The degree 10 to which the valve may open is limited by means of the adjustable stop 35. At the outer end of the horizontal portion 32 I preferably provide a hinged pop valve 36 which will, of course, be normally closed but which will 15 open upon backfiring so as to relieve the pressure.

Preferably means will be provided for warming the air in the clean air outlet pipe 16, and before its passage to the carbureter, 20 and to this end I provide a rubber elbow 37 which fits over the $1\frac{1}{2}$ " brass pipe 33 and which is connected to a pipe 38 which extends over the exhaust manifold so that heat in the exhaust manifold may transmit its 25 heat to the air in the clean air outlet pipe 16 and 38 and thus warm the cleaned air prior to its entrance to the manifold. The lower end of the jar 10 will be provided with a drain cock 39. The water tank from which water 30 is delivered to the jar 10 is preferably of brass and is provided with a sediment trap 40 and has means at one end whereby the height of water may be determined. A rubber pipe 22 extends from the water tank to the pipe 21, 35 as heretofore described.

The tube sheet which is attached to the lower end of the dome and which rests upon the top of the jar or tank 10 extends beyond the jar or tank. This jar or tank rests upon 40 a bracket 42 and bolts 41 pass down through the projecting margin of the tube sheet and through the bracket and thus hold the jar or tank in place upon the bracket and the dome tightly against the gasket in the upper end of the tank or jar.

The operation of this mechanism will be obvious from what has gone before. Upon every suction stroke of the engine, the valve 50 34 opens and the cleaned air is drawn out through the pipe 16 from the upper portion of the jar 10. This draws air downward through the pipes 17 from the dome 14 and through the intake pipe 20. The air is obliged to pass downward through the pipes 55 17 and through the layer of water in the bottom of the jar and then upward through the screen 19 into the upper portion of the jar. Thus, the air is thoroughly cleansed

and particles of dust, carbon, and other foreign matters are detained in the bottom of 60 the jar. The air is moistened prior to its passage to the carbureter and is thus in the best possible condition for use. Actual tests have shown that the use of this washer will 65 greatly increase the mileage per gallon, that the motor will run much more smoothly and give much more power and there will be less carbon deposit within the cylinders. While I have heretofore referred to the use 70 of water in the bottom of the washing jar 10, oil may be used in freezing weather instead.

I claim:—

1. An air cleaner for motor cars comprising a tank having a removable dome at its upper end, a partition extending across the dome at the lower end thereof and soldered to the dome throughout its entire circumference, the wall of the tank being formed with a seat, a packing ring disposed in said seat upon which the partition rests, air pipes opening through said partition and carried thereby and extending downwardly nearly to the bottom of the tank, a bubble sheet through which the air pipes pass and extending transversely across the tank above the bottom thereof and having a plurality of openings, an air inlet pipe entering the dome, and an air outlet pipe entering the dome and extending through the first named partition 90 and carrying a check valve in its length.

2. An air cleaner for motor cars comprising a tank containing liquid, a removable dome at its upper end, a tube sheet carried by the lower end of the dome and attached thereto throughout its entire circumference and when the dome is in position extending entirely across the tank, the tank being formed at its upper end with a seat, a packing ring carried thereby upon which the tube 95 sheet rests, a plurality of air pipes carried by and depending from and opening through the tube sheet, a bubble sheet carried by the pipes between the upper and lower ends thereof and having a plurality of openings between the pipes, said bubble sheet fitting loosely within the tank, an air inlet pipe entering the dome, an air outlet pipe extending from the tubular sheet and opening therethrough and provided with a check valve, and 100 automatic means for maintaining the level of liquid in the tank.

In testimony whereof I hereunto affix my signature.

TOMAS FRANKLIN GERKEN.
